UNITED STATES PATENT OFFICE.

MILTON B. REACH, OF SPRINGFIELD, MASSACHUSETTS, ASSIGNOR TO R. P. K. SPECIALTY CO., A CORPORATION OF NEW YORK.

SHOE-FORM.

No. 927,281.

Specification of Letters Patent.

Patented July 6, 1909.

Application filed January 29, 1909. Serial No. 474,976.

To all whom it may concern:

Be it known that I, MILTON B. REACH, citizen of the United States, residing at 75 Avon Place, Springfield, Massachusetts, have invented certain new and useful Improvements in Shoe-Forms, of which the following is a specification.

My invention relates to shoe forms, and while particularly adapted for use with ladies' slippers, I do not limit myself in this respect.

One object of my invention is to provide a form of simple, light and economical construction that may be readily placed in position and moved therefrom by the user.

The invention consists in the feature and combination and arrangement of parts hereinafter described and particularly pointed out in the claims.

20 In the accompanying drawings, Figure 1 is a bottom plan view of a shoe form embodying my invention. Fig. 2 is a central longitudinal section of Fig. 1, and Fig. 3 is a transverse section substantially on the line 3—3 of Fig. 1 with parts broken away. Fig. 4 is a detail view of a modification.

I prefer to make the form of sheet aluminum, this having the quality of lightness and sufficient strength when properly reinforced. 30 The main portion of the form is indicated at 1, consisting of a single sheet of material having the arched portion and bottom portions 2—2, these bottom portions having a crevice between them at 3 and terminating at their 35 front ends with rounded edges 4 somewhat in rear of the extreme toe portion of the form, leaving a space at 5 between the sole portions and the edge of the upper or arched portion.

40 The form is reinforced in order to give the sheet aluminum the necessary degree of stiffness and strength. This reinforcing piece consists of a back plate 6, formed preferably of steel having forwardly extending flanges 7 and 8 fitting within the rear portion of the form and through these flanges and the sheet metal of the form rivets or securing bars 9 extend, so as to connect the reinforcing plate with the sheet aluminum main portion. The 45 flange 7 extends across the crevice between the portions of the bottom of the form and serves to connect these bottom portions together.

The straining rod or spring consists of a 50 thin strip of metal 10 having a clip 11 at its

rear end of substantially cylindrical form and riveted at 12 to the straining spring or rod, this clip affording a bearing at the rear to engage the heel or counter of the shoe or slipper. At its forward end the spring straining member passes through an opening at 13, in the back reinforcing plate 6 and is riveted to a bracket 14, secured to the inner face of the back plate, a single rivet being sufficient for this purpose. The opening 13 confines the 60 straining spring closely in position and together with the rivet securely maintains the straining rod or spring in the position desired.

It will be observed that the rivets or securing rods 9 pass from the top to the bottom of the form through the flanges of the reinforcing plate and through the sheet aluminum. This affords a strong construction and is particularly of advantage where an aluminum sheet is employed, which of course is of a soft 70 quality.

I do not limit myself to the particular construction of the back plate shown, as this may be in the form of a strut, as indicated in Fig. 4.

I do not limit myself to the use of a separate supporting piece 14, as this may be struck out of the metal of the back plate.

While I have shown a spring having a straight end secured to the bracket on the back plate, I do not limit myself in this regard as the spring may have its end turned and suitably secured to the back plate, and it will be obvious that various details of construction may be changed without departing 90 from the spirit of my invention.

I claim:

1. In combination with the main portion of the form having the arch portion and the two bottom portions the latter portions being separated by a crevice, a reinforcing back plate extending from the arch portion to the bottom portions and across the crevice between the said bottom portions, said reinforcing piece being secured to the arch and bottom portion, substantially as described. 95

2. In combination with a main portion, a reinforcing piece having the flanges engaging the arch and bottom of the main portion and the rivets passing from the arch through the flanges to the bottom of the main portion, substantially as described. 105

3. In combination in a shoe form the main portion, a reinforcing member at the rear thereof having an opening, a straining mem- 110

ber passing through the said opening and means for securing the said straining member within the form, substantially as described.

5. 4. In combination in a shoe form, the main portion, a back plate having an opening therein, a straining member extending through the said opening and connected at its inner end to the back plate on the inner side thereof, substantially as described.

5. In combination in a shoe form with a main portion, a back plate having an inwardly extending lug or projection and having an opening and a straining member extending through the opening and secured to said projection, substantially as described.

6. In combination in a shoe form with a main portion having a back plate with an

opening therein, a spring strip forming a straining member passing through the opening and secured at its inner end within the form, substantially as described.

7. In combination in a shoe form of sheet metal having an arched portion and two bottom portions, with a crevice between them, said bottom portions at their front ends having an opening between them and the edge of the arch portion at the toe and a back plate extending across the bottom portion and secured thereto, substantially as described.

In testimony whereof, I affix my signature in presence of two witnesses.

MILTON B. REACH.
